UNITED STATES PATENT OFFICE.

ROBERT LEWIS JOHNSON, OF HANLEY, ENGLAND.

DESIGN FOR A VEGETABLE-DISH.

SPECIFICATION forming part of Design No. 35,863, dated April 15, 1902.

Application filed February 12, 1902. Serial No. 93,803. Term of patent 3½ years.

To all whom it may concern:

Be it known that I, ROBERT LEWIS JOHNSON, a subject of the King of England, residing at Hanley, in the county of Stafford, England, have invented and produced a new and original Design for Vegetable-Dishes, of which the following is a specification, reference being had to the accompanying drawings, forming part thereof, in which—

Figure 1 is an elevation representing my design for a vegetable-dish, and Fig. 2 is a plan view of the same.

As shown in the drawings, the vegetable or cover dish is of conventional shape, and the leading or essential features of my design consist in the ornamental knob disposed at the center of the cover and the adjacent leaflet, ornaments on the central portion of the cover, and the ornamental handles disposed at the ends of the body of the dish.

The design of the ornamental knob at the center of the cover, of conventional shape, comprises the quarter-foil leaflet ornaments *a* and central rosette *b*, and the design of the cover comprises the diverging leaflet ornaments *c*, adjacent to the knob and at the highest and central portion of the cover. The edge *f* of the cover is scalloped, and adjacent

thereto and conforming therewith are pearl ornaments *g* and lines indicating a rib *h*.

The design of the body of the dish, of conventional shape, comprises the handles *d*, disposed at the ends thereof and of curved form in side elevation and each comprising edge leaflet ornaments *e* and curved ribs *e'*, surrounding the opening therein. Disposed around the upper and lower portions of the body are pearl ornaments *i* *i'*, and there are scroll and leaflet ornaments *k* *k'* disposed at the respective ends of the body, starting near the base thereof and extending in opposite directions at the ends toward and terminating at the handles *d*.

Having described my invention, what I claim as new, and desire to secure by Letters Patent, is—

The design for a vegetable-dish, substantially as herein shown and described.

In testimony whereof I have signed my name to this specification in the presence of two subscribing witnesses.

ROBERT LEWIS JOHNSON.
